(57) **CLAIM**

The ornamental design for an orthotic footbed, as shown and described.

DESCRIPTION

FIG. 1 is one perspective view of an orthotic footbed, according to the design.

FIG. 2 is another perspective view of the orthotic footbed of FIG. 1.

FIG. 3 is a top view of the orthotic footbed in FIG. 1.

FIG. 4 is a bottom view of the orthotic footbed in FIG. 1.

FIG. 5 is a left side view of the orthotic footbed in FIG. 1.

FIG. 6 is a right view of the orthotic footbed in FIG. 1.

FIG. 7 is a front view of the orthotic footbed in FIG. 1; and,

FIG. 8 is a rear view of the orthotic footbed in FIG. 1.

The broken lines shown in the FIGS. illustrate environmental subject matter or portions of the article that form no part of the claimed design.

FIGS. 1-8 illustrate orthotic footbed for a right foot. Orthotic footbed for a left foot is a mirror image.

1 Claim, 7 Drawing Sheets
